UNITED STATES PATENT OFFICE.

MURRAY A. STOVER, OF EL CENTRO, CALIFORNIA.

SAXOPHONE.

1,146,368.

Specification of Letters Patent. Patented July 13, 1915.

Application filed August 19, 1913. Serial No. 785,501.

To all whom it may concern:

Be it known that I, MURRAY A. STOVER, a citizen of the United States, residing at El Centro, in the county of Imperial, State of California, have invented new and useful Improvements in Saxophones, of which the following is a specification.

This invention relates to saxophones, and the principal object is to provide a simpler 10 method of fingering to form the high notes on the instrument, and also the note G sharp.

It is also an object of this invention to provide a mechanism, whereby certain notes may be produced by the operation of a lesser 15 number of keys, than in usual instrument constructions.

A further object is to provide a simplified arrangement of operating keys so that the same may be more readily reached during 20 an operation of the instrument.

It is a further object to provide a saxophone with a system of keys in which it is simpler to form trills and high octave passages.

25 The invention is illustrated in the accompanying drawings, in which:

Figure 1 is an elevation of the right side of a saxophone, showing the invention applied thereto. Fig. 2 is an enlarged detail of 30 a portion of the right side of the instrument showing the present invention applied to a standard model. Fig. 3 is a section on the line 3—3 of Fig. 2 viewed in the direction indicated by the arrows. Fig. 4 is a section 35 on the line 4—4 of Fig. 2. Fig. 5 is a detail in elevation of a portion of the mountings for automatically closing the high-E and F pads and pad 70. Fig. 6 is a detail showing the device for operating the G-sharp pad. 40 Fig. 7 is a detail in side elevation showing the torsion spring for operating the sleeve to which is attached the finger piece for operating the G-sharp pad. Fig. 8 is a detail section on the line 8—8 of Fig. 7. Fig. 45 9 is a section on the line 9—9 of Figs. 2 and 10. Fig. 10 is an enlarged detail view of the upper portion of the left side of the instrument above the line A—A of Fig. 11, showing the E flat, F and D pads. Fig. 11 is a 50 detail of the lower portion of the left side of the instrument below the line A—A of Fig. 10, showing the construction of the sleeves necessary to operate the high D and E flat pads. Fig. 12 is a view of the left side 55 of the instrument on a scale corresponding to the view shown in Fig. 1. Fig. 13 is an

enlarged detail of a portion of the upper left side of the instrument showing how the E flat and D pads are opened, and also the manner in which the opening movement of 60 the E flat pad automatically closes the F pad.

Heretofore in the operation of fingering the finger pieces to form high tones in a saxophone, the fingering to produce the high 65 notes has been difficult and the fingering for octave passages extremely so, requiring great agility, and more arduous labor in performing upon the instrument especially in the operation of the palm pieces. This invention 70 overcomes this difficulty in providing finger pieces more conveniently placed on the instrument so that the palm pieces may be entirely eliminated at the option of the performer and the fingering more simply 75 produced, resulting in greater efficiency.

The improved mechanism comprises means for operating: pad 12 for F carried by finger piece 11; pad 16 for E carried by sleeve 18 and operated by finger piece 19; pad 39 80 for E flat carried by finger piece 38 and controlled by arm 37; pad 41 for D flat carried by finger piece 41' also controlled by arm 37; pad 96 for G sharp controlled by finger 85 piece 85.

The highest note which can be produced on the instrument shown is F above the staff, this note being produced ordinarily by pressing the finger piece 11 disposed adjacent the upper end of the instrument which is connected directly to and lifts the pad 12, shown at the upper part of Figs. 1 and 2. In my improved instrument the pad 12 on the finger piece 11 is normally held in a closed position by means of a lug 14 on the high-E 90 pad 16 arranged adjacent the high-F pad 12, in opposition to a spring 15, particularly shown in Fig. 13, which spring 15 will 95 operate the finger piece 11 to open the high-F pad 12 when the high-E pad 16 is open. The opening of the high-E pad 16 is effected by rocking a sleeve 18 on which it is mounted; the sleeve 18 being operated by means of a finger piece 19 attached thereto and disposed on the lower portion of the instrument. The sleeve 18 is oscillatingly mounted upon a shaft 20 extending longitudinally of the instrument and is formed with an off-set portion 21. A second sleeve 22 is mounted on the shaft 20 and extends parallel with the off-set portion 21 of the sleeve 18. 100 105 110

To eliminate the operation of the finger

piece 19 by the palmar joint of the first finger of the right hand a finger piece 24 is mounted on a rock-shaft 25 which is freely turnable on the shaft 26 and which rock-shaft 25 has an arm 27 rigidly connected therewith. The arm 27 extends toward the finger piece 19 and is provided with a finger 28 which engages with an arm 29 on a sleeve 30; this sleeve being oscillatingly mounted upon a shaft 31 extending parallel with the shaft 20 and spaced a short distance therefrom. The arm 29 is extended to project on the opposite side of the sleeve 30 and has an elongated finger 32 thereon extending parallel with the sleeve 30 and which engages with a spring 33 rigidly connected to the sleeve 18, so that by depressing the finger piece 24 the E pad 16 is lifted, together with its arm 14, and allows the F pad 12 to open. The F pad 12 must be closed when producing the note E flat above the staff. The finger piece 11 intermediate of its pivot 35 and the pad 12 is provided with a hump 36 which allows the arm 37 normally found on the instrument to move outwardly without affecting this pad. The arm 37 is extended around the tube 10 of the instrument, as shown in Fig. 9, to engage under the finger piece 38 connected to the E flat pad 39 and extended beyond this point, under the lug 40 secured to the upper edge of the D pad 41 carried by the finger piece 41'. This arm 37 is affixed to a sleeve 42 mounted on the short shaft supported between the brackets 43 and is extended beyond the sleeve to form a longitudinally disposed finger 44 which projects under a finger 45 secured to the sleeve 22 previously mentioned.

40 Formed on the sleeve 22 and extending in the same direction as the finger 45 is a second finger 46 which passes under the shaft 31 and is adapted to close the pad 47 over which it extends. The pad 47 is held open by means of a spring connected to the sleeve 48 on which it is mounted. Close to the lower end of the sleeve 22 is a third finger 49 extending from the same side of the sleeve as the fingers 45 and 46, which finger 49 is adapted to engage with a bent arm 50 mounted on a sleeve 51 freely mounted upon a shaft 52, this sleeve 51 being intermediate of an off-set formed on a second sleeve 53 mounted on the same shaft.

55 Immediately below the lever 49 on the sleeve 22 is a short finger 55 which engages with a bent arm 56 forming an extension of an arm 57 supporting the pad 58, this pad being normally held open. The arms 56 and 57 are carried on the sleeve 60, which is provided with an off-set 59, carrying the finger piece 61, as shown in Fig. 3.

To effect the operation of the sleeve 51 it is provided with an arm 62 which extends parallel with the finger piece 24, the arm

62 overlapping the pad 63 so that a finger piece 65 on the arm 62 is in convenient position to be depressed by the second finger while the first finger holds down the finger piece 24, this action opening the pad 16, closing the pad 12, and opening pads 39 and 41 through the medium of the arm 37. In this operation the action of the spring 15 must be overcome, and to accomplish this a second spring 66 is interposed and secured to the lower end of the finger piece 11 by means of screws 67, as shown in Fig. 13; the forward end of this spring 66 extending under a notch 68 formed in the finger piece 11; mounted on the finger piece 38 a stud 69 extends under the finger piece 11 and bears upon the free end of the spring 66, it being understood that the spring 66 is stiffer than the spring 15. The spring acting upon the sleeve 22 is of sufficient strength when released by the bent arm 50 to press down the finger piece 44 and lift the pads mentioned, namely, 39 and 41. A stronger spring acting upon the sleeve 51 causes the bent arm 50 to press upward on the finger 49 counteracting the action of the spring acting upon the sleeve 22, allowing the pads 39 and 41 to remain closed normally.

The saxophone is provided with the usual normally-open pad 70, the office of which is to form the note C and notes below, when closed, and C sharp when opened. Pad 70 is carried on an arm 71, attached to a sleeve 23, mounted to oscillate on shaft 31, the arm being continued beyond the sleeve 23 and connected with the downwardly-extending bar 72, as particularly shown in Figs. 4 and 5.

The formation of D sharp or E flat above the staff is automatically effected by releasing the finger piece 24 whereupon the E pad 16 closes and the proper note is formed, the pad 70 remaining open, since the arm supporting the pad 47 does not engage the bar 72, and the pad 47 may be operated by means of the finger piece 46 independently and without closing the pad 70, thus producing a perfect D sharp or E flat.

To enable the production of the tone B a second sleeve 23' is interposed on the shaft 31 between the sleeve 23 carrying the pad 70 and the sleeve 48 carrying the pad 47, which sleeve 23' carries an arm 73 bent around in such position that its finger piece 74 when depressed depresses the pad 47 and also the pad 70 since the opposite end of the arm 73 engages with the bar 72, as shown in Fig. 5.

To make high D the second finger of the left hand depresses the finger piece 80 disposed near the outer end of the finger piece 11, which closes the pad 81 directly thereunder but not connected therewith, this finger piece 80 being mounted on an arm 82

which is secured to a sleeve 83 carrying the pad 84, as shown in Fig. 3, which pad 84 is also closed by this operation of the key 80. The arm 82 is extended in the opposite direction 5 and engages the inner side of the bar 72 so that the pad 70 is closed coincidentally with the pads 81 and 84, which lowers the pitch from D sharp and produces a perfect D, it being understood that the finger piece 10 65 is depressed at the same time to open pads 39 and 41 and close 47.

G sharp is produced by operating the finger piece 85, which is secured to the lower end of the sleeve 86 mounted on a shaft immediately beneath and parallel with the shaft 20 and supported in the same pedestals 87, the upper end of this sleeve being provided with an arm 88 which extends under the lower end of the arm 89 pivoted on the 15 sleeve 90 to which is secured the pad 91. The pad 91 is held shut by the stress of the spring 92, as clearly shown in Figs. 7 and 8, this latter spring 92 being of greater tension than the spring 93 secured to the arm 20 89 so that when the finger piece 85 is depressed the spring 93 will open the pad 91. Also secured to the sleeve 86 is an arm 94 which is extended in the opposite direction, its outer end falling under a lug 95 formed on 25 the G sharp pad 96 so that when the arm 85 is depressed this pad will be opened and the note desired produced, namely, G sharp.

To counteract the action of the spring 93 and hold the pad 91 closed when the G sharp 30 is being produced, the arm 82 is extended beyond and under the bar 72 and engages with the arm 89 just above the arm 88, the finger piece 80 being depressed also at this time.

40 In order to avoid releasing the finger piece 24 in passing from high F to medium or low F, the pads 12 and 16 may be closed by the first or second fingers of the left hand in closing the pads 47 or 81 by depressing the 45 finger pieces 74 or 80 to move the bar 72. The bar 72 engages an arm 98 mounted on the offset 21 of the sleeve 18, as shown in Fig. 4, in such manner as to rock the sleeve 18 and thereby close the pads 12 and 16 50 while the finger piece 24 is depressed; the spring finger 33 permitting the movement of the sleeve 18 independent of the finger piece 24.

To avoid releasing the finger piece 65 in 55 passing from high E to medium or low E, or other notes employing the second finger of the right hand, pads 39 and 41 may be closed by the third finger of the left hand depressing the finger piece 61. By depressing the finger piece 61 the sleeve 60 is rocked and the pad 58 is closed; the arm 56 on the sleeve 60 engaging with the finger 55 rocks the sleeve 22 and raises the finger 45 to release the curved arm 37 and permit the closure 60 of the pads 39 and 41.

The note E flat or D sharp is usually made, in ordinary makes of saxophones, by opening pads 39 and 41, the pads 70, 47, 81 and 84 remaining open also, while in my system this note is made by opening the same 70 pads 39 and 41, but the pad 47 is closed by the finger 46 fixed to the same sleeve 22 which operates pads 39 and 41; the pads 70, 81 and 84 remaining open. Now the closing of a number of pads immediately below 75 the pads 39 and 41 when they are open to produce D sharp or E flat, tends to flatten the pitch, and I take advantage of this fact by closing the pads 70, 47 and 81 and 84 to produce the note D, the pad 47 being automatically closed by the finger 46 and the pads 70, 81 and 84 being closed by the second finger of the left hand depressing the key 80, which lowers the pitch from E flat or D sharp to a perfect D, as before stated; 80 the pads 39 and 41 remaining open of course, and my only object in having pad 47 automatically closed by the finger 46 is to avoid the use of the first finger of the left hand in conjunction with the second finger in 85 making the D note.

By way of explanation I will further state that the note C is made with the second finger of the left hand alone by depressing finger piece 80 which closes pads 70, 81 and 90 84, the pad 47 remaining open. Therefore, in order to trill from C to D by my system it is only necessary to depress the finger piece 65 with the second finger of the right hand. This operation rocks sleeve 51 and 95 sleeve 22 through arm 50 and finger 49 and thereby operates through finger 45 and arm 37 to open the pads 39 and 41 and automatically close pad 47 to produce a perfect 100 D. To pass from D to D sharp or E flat it 105 is only necessary to raise the second finger of the left hand from the finger piece 80 allowing the pads 70 and 84 to open to produce a perfect D sharp or E flat, but this tone would not be perfect if pad 70 remained 110 closed, which is my only reason for arranging the mechanism so that the pad 47 can be closed automatically by the finger 46 without closing the pad 70. The closing of the pad 47 is not necessary in producing D 115 sharp or E flat, but is unavoidable, because of my method of producing D, and while its being closed in the production of D sharp or E flat would tend to flatten the tone this is not perceptible if the pad 70 remains 120 open.

What I claim is:

1. A saxophone having a normally closed F pad provided with a finger piece for opening the same, a normally closed E pad, 125 means on the E pad for holding the F pad in its normally closed position and spring means for opening the F-pad on opening of the E-pad.

2. A saxophone having a normally closed 130

high-F pad, a lever connected therewith, a spring acting on said lever tending to open said pad, a high-E pad, a lug projecting from said pad adapted to engage said F pad, means to normally close said E pad, and means to open said E pad, whereby said F pad is also opened to produce high-F.

3. A saxophone having an F pad, E pad, means to normally hold each of said pads closed, a spring adapted to open said F pad, a normally closed E-flat pad, a normally closed D pad, means intermediate said F pad and said E flat pad, whereby the opening of said E-flat pad will overcome said spring and hold the F pad closed, and means operable to open said E pad, E-flat pad, and D pad, whereby high-E will be produced.

4. A saxophone having an F pad, and E pad, means to normally hold each of said pads closed, a spring adapted to open said F pad, a normally closed E-flat pad, a normally closed D pad, means intermediate said F pad and said E-flat pad, whereby opening of said E-flat pad will overcome said spring and hold the F pad closed, and means to open said E flat and D pads, whereby the note E flat may be produced.

5. A saxophone having an F pad, an E

pad, means to normally hold each of said pads closed, a spring adapted to opening said F pad, a normally closed E-flat pad, a normally closed D pad, means intermediate said F pad and E-flat pad, whereby opening of said E-flat pad will overcome said spring and hold the F pad closed, means to open said E-flat and D pads, a series of pads 47, 70, 81 and 84, and means to close pad 47, together with pads 70, 81 and 84, whereby the note D natural may be produced.

6. A saxophone having a normally closed G-sharp pad, a lug projecting therefrom, a pivoted arm adapted to engage said lug, a sleeve carrying said arm, an operating finger piece on said sleeve adapted to be depressed by the right hand of an operator thereof, a pad 91, and means connected with the finger piece to open pad 91, whereby a true G sharp note is produced.

In witness that I claim the foregoing I have hereunto subscribed my name this 12th day of Aug., 1913.
